UNITED STATES PATENT OFFICE.

CHARLES B. DARRIN AND MARC DARRIN, OF BELLINGHAM, WASHINGTON.

RETORT.

1,074,104.

Specification of Letters Patent. Patented Sept. 30, 1913.

Application filed December 16, 1911. Serial No. 666,309.

To all whom it may concern:

Be it known that we, CHARLES B. DARRIN and MARC DARRIN, citizens of the United States, residing at Bellingham, in the county of Whatcom and State of Washington, have invented a certain new and useful Improvement in Retorts, of which the following is a specification.

Our invention relates to improvements in retorts employed in the operations of extracting distillable matter from wood and other carbonaceous material whereby such matter together with the residue of charcoal, coke or other form of carbon may be saved, but more particularly it relates to a retort with its necessary auxiliary devices whereby successive car loads of carbonaceous material may enter one end of such retort and each of such loads, in its passage therethrough, successively be subjected to varying conditions of heat during its progress to the other end, from which it emerges in the form of nearly pure carbon; its different kinds of distillable matter having each been separately extracted at a different point within such retort during its journey therethrough; and the object of our improvement is to provide a single structure which shall constitute a retort embodying a longitudinal succession of intercommunicating compartments, within each of which compartments the material to be retorted independently may be subjected to a desired treatment, and which shall be simple in construction, durable and have a high fuel efficiency. We attain this object by devices illustrated in the accompanying drawing in which—

Figure 1 is a diagrammatical view in side elevation indicating some of the essential features of our invention. Fig. 2 is a diagram in vertical-section on lines *w-w* of Fig. 1 of same. Fig. 3 is a diagram in vertical-section on line *x-x* of Fig. 1 of same. Fig. 4 is a diagram in vertical-section on line *y-y* of same. Fig. 5 is a diagram in vertical-section on line *z-z*, and Fig. 6 is a diagram of a plan-view of our invention.

Like reference numbers indicate like parts throughout the drawings.

Referring to Fig. 1, therein are shown sections 9—10—11—12 and 13 of a retort, which sections are connected together by expansion joints 14 to form a single structure. The ends of said retort are each provided with a gate 15, which is adapted to be raised or lowered to open or close it by force acting

through a piston rod 16 which piston rod 16 is indicated in Fig. 1 as extending upward from each end of said retort. Hydraulic or other suitable devices may be employed such as the cylinders 17 to actuate such piston rod 16 or other device for controlling said gate. Each section between adjacent joints 14 is formed to have a shape shown in cross-section by Fig. 2. The said sections 9—10—11—12 and 13 preferably may be made of iron plates or of steel plates, though common brick, fire brick or other suitable material might be used in some cases. The sections 9—10—11—12 and 13 are shown in Fig. 1 as being disposed to rest upon a number of rollers 18 which rollers serve to permit free longitudinal movement of said sections due to expansion or contraction thereof and which are disposed upon a series of inclined girders 20, which extend between and are supported by the gate supports 19, whereby one end of the retort is higher than the other to provide drainage. Leading into the tops of sections 9 and 13 are the pipes 21 which may be connected with a source of live steam not shown. At the bottom of the lower end of each of sections 10—11 and 12 are disposed drain pipes 22 through which may pass the heavier matter which may exude from the material operated upon.

From the top of section 10 are two outlet passages 23 which are connected by suitable elbows, pipes and a T to a pipe 24 which may conduct distilled matter to a receptacle not shown. Also from the tops of sections 11 and 12 are other systems of pipes each system comprising four upright pipes 25 having closed tops and from near each of which tops extends downwardly at an angle of about 45 degrees a pipe 26 which is connected with one of four upright stand-pipes 27 which are all connected at their top ends with a horizontal pipe 28 from which a pipe 29 may lead to a receptacle not shown, for lighter distilled products. Each of the stand-pipes 27 is provided with a smaller outlet pipe 30 through which heavier products of distillation may flow to a suitable receptacle as indicated in Figs. 4 and 5. The stand-pipes 27 are each further provided with a smaller pipe 31 which enters at the top thereof and projects through its side near its bottom as indicated in Figs. 4 and 5 by dotted lines. This smaller pipe 31 in practical operation is supplied with cold water whereby it may serve to cool and con-

ucts are subjected to the presence of the water-cooled pipes 31 disposed within the standard-pipes 27 whereby some of the volatile products are condensed and drained into 5 a suitable receptacle through drain pipe 30 while the most volatile products rise and flow to another suitable receptacle through pipe 29. Again, after a suitable period of time the car 40 is moved in a similar manner 10 into section 12 which is of still higher temperature and within which the material in car 40 is subjected to similar treatment while the products exuding from such material are disposed of in a manner similar to that 15 which occurred in section number 11. After the material has remained sufficiently long in section 12 it is inducted into section 13 where it is subjected to live steam which may enter through pipe 21, which live steam 20 serves to cool the material in car 40 which now consists almost wholly of pure carbon whereby its temperature is reduced below the point of combustion whereupon the car may be caused to emerge from the lower end 25 of the retort to dispose of its carbonized residuum. This operation may be continuous; that is, as fast as cars are moved from one section into another they may be replaced by other loaded cars, thus fresh carloads of 30 raw material successively are pushed into the live steam entrance section 9 and successively passing through the several sections 10-11 and 12 thence pass successively from section 13. 35 The vapors which pass from the pipe 24 leading from section 10 to a suitable receptacle contain volatile constituents in a nearly pure, unburned, non-empyreumatic and easily refinable state. The vapors from retort 40 section number 11 passing through the condenser standard-pipes 27 give up the greater part of the heavy tar constituents which have always caused trouble in subsequent refinement, such heavy tar constituents draining 45 from pipes 30. Such vapors, after traveling through the standard-pipes 27, are thus in a more easily refinable form. Vapors from section 12 are treated in an identical manner with those from section 11. 50 When desired an exhaust pump may be employed in an obvious manner to hasten the removal of vapors from any of the sections. It will be observed that wood or other material when placed within the car 40 permits 55 the pitch and tar to trickle downward and drip on to the less heated floor bottom to be drained off without decomposition. The hot tar condensers associated with pipes 26 and

standard-pipes 27 greatly aid a subsequent refinement of volatile products. 60

Manifestly our retort may be made to embody any number of sections of any length that may be commercially desirable and it may be of any desired shape in cross-section, but preferably narrow, as the heat is applied 65 to its sides by furnaces and flues and by superheated steam pipes to heat quickly and thoroughly the material treated; and the bottom of the retort is thus maintained at such lower temperature as will prevent injury by over heating of the drippings from the material treated. 70

Of course, the cars 40 may be modified in plan of construction, as for instance, they might have wheels to run on a track which 75 might be substituted for the rollers on the floor of the retort and the sides and tops of such cars 40 might be of different forms.

What we claim is:

1. A retort having compartment sections, 80 a flue disposed over the central ones of said sections, the inlet portion of said flue being enlarged, steam pipes conducted through said flue and interiorly of a portion of said sections and exhausting into the terminal 85 one thereof positioned within said flue, a furnace positioned within the enlarged inlet portion of the flue, and an exhaust outlet pipe for said flue.

2. A retort consisting of a plurality of 90 compartment sections, steam pipes entering the terminal ones of said sections, a flue disposed over the remaining central ones of said sections, the inlet portion of said flue being enlarged, a furnace positioned within 95 said enlarged flue portion and surrounding one of said sections, an exhaust outlet pipe at the opposite end of said flue, steam pipes extending through said enlarged flue portion and within said furnace, said steam pipes 100 passing through the middle one of said flue inclosed sections and entering and exhausting within the section lying adjacent the flue exhaust outlet.

In witness whereof, we hereunto subscribe 105 our names this 25th day of November A. D. 1911.
